(57) **CLAIM**

The ornamental design for a headlight for construction equipment, as shown and described.

DESCRIPTION

FIG. 1 is a perspective view of the headlight for construction equipment according to the invention;

FIG. 2 is a front elevation view of the headlight for construction equipment of FIG. 1;

FIG. 3 is a rear elevation view of the headlight for construction equipment of FIG. 1;

FIG. 4 is a right side elevation view of the headlight for construction equipment of FIG. 1;

FIG. 5 is a left side elevation view of the headlight for construction equipment of FIG. 1;

FIG. 6 is a top plan view of the headlight for construction equipment of FIG. 1; and,

FIG. 7 is a bottom plan view of the headlight for construction equipment of FIG. 1.

The broken lines in the drawings illustrate portions of the headlight for construction equipment which form no part of the claimed design.

The line shading in parts of the drawings is included for the purpose of illustrating use and environment and forms no part of the claimed design.
